UNITED STATES PATENT OFFICE

ROY R. HART, OF SAN JOSE, CALIFORNIA

RACK FIXTURE

Application filed July 24, 1931. Serial No. 552,836.

This invention relates to devices for disengageably supporting the handles of brooms, mops and the like to hold them in a vertical position. The fixture is of that type in which the holding engagement of the handle is automatically had with the downward pull of the latter by reason of its own weight. I have found from experience that the holding aperture to be operative and effective must nearly fit the handle when said aperture lies in a plane at right-angles to the handle. It is not therefore feasible to use a single aperture to engage handles of any great range of diameter and yet to be commercially practicable for household use a single fixture should be capable of taking care of any handles within the size range likely to be encountered.

The major object of the present invention therefore is to construct a single holder in such a manner as to effectively engage and hold handles of a number of different sizes.

As another object of the invention I have constructed the device so that a firm holding grip on any handle is obtained without the use of prongs, teeth or other sharp edged elements which cut into soft wood handles and not only mark the same but cause splinters to develop.

A further object of the invention is to produce a simple and inexpensive device and yet one which will be exceedingly effective for the purpose for which it is designed.

These objects I accomplish by means of such structure and relative arrangement of parts as will fully appear by a perusal of the following specifications and claims.

In the drawing similar characters of reference indicate corresponding parts in the several views:

Fig. 1 is a perspective view of my improved fixture as mounted in place and supporting a broom handle.

Fig. 2 is a transverse view of the fixture as in operation and partly in section.

Fig. 3 is a perspective view of the device detached.

Referring now more particularly to the characters of reference on the drawing, the device comprises a bracket which consists of

a flat plate 1 having holes 2 whereby it may be secured against a wall at a convenient height by screws 3. The bracket is preferably made of sheet metal and at its sides is formed with outwardly bent ears 4 having horizontally aligned circular openings 5 therethrough.

The handle engaging or gripping member of the device comprises a plate 6 having opposed side lugs 7 at its back edge which project into and are turnable in the holes 5. Since the ear holes are a greater distance from the wall than the thickness of the plate 6, said plate if swung up until it rests against the wall will then fit at a backward slope 65 which prevents said plate from swinging out and down of itself. The downward movement of the plate a predetermined distance below a horizontal position is prevented by stop shoulders 8 formed on the ears below 70 the holes 5 and adapted to engage the under side of the plate 6, which is cut and shaped so as to extend beyond the ears in front of the same as shown.

The plate 6 is provided with a relatively 75 long aperture 9 open to one side of the plate and whose major axis is parallel to the bracket plate. Said aperture is formed so that it consists of a number of portions of definitely different and successively decreasing width 80 from its outer to its inner end as shown at 10, 11 and 12. These different widths are in proportion to and somewhat larger than the diameter of a number of handles of different sizes, so that any handle likely to be encountered may be engaged by the one fixture. In certain cases it is probable that a pair of 85 these different widths of the opening would be sufficient for all uses.

All the said different width portions of the 90 aperture are narrower at their outer than at their inner ends, so that a handle when placed in position is prevented from possibly slipping outwardly and tends to move between and engage shoulders 13 formed at the junction of said different width portions.

As stated the holding action is more effective if the plate is maintained as nearly horizontal or at right-angles to the handle as possible. To attain this end the plate at the 100

back end of the aperture is formed with a downward reversing or double bend as at 14, so that the front portion of the plate while parallel to the back portion is on a lower 5 level as indicated by the dash lines L in Fig. 2; and the corresponding sides of the aperture throughout their extent are also on different levels. This is plainly shown in Fig. 2. As a result the plate itself may be 10 disposed nearly horizontal while at the same time the opposed points of engagement of the sides of the aperture with the handle are vertically spaced to a greater extent as is necessary to give the frictional grip. An effective 15 grip is thus obtained without the use of sharp edges, prongs or the like. The action is the same as if the plate were made of relatively thick metal, in which case the handle to be engaged on one side by the opening at 20 the top edge of the blade and on the opposite side by the bottom edge of the opening. By my construction I am enabled to use relatively thin sheet metal in making the plate, as is desirable for economy of manufacture and 25 other reasons. This thin plate is reinforced by a raised rib 15 which extends about said plate substantially symmetrical with the aperture.

In operation the plate 6 is raised to a horizontal 30 position and the handle 16 of the broom, etc. is held in a vertical position and is moved toward said plate and into the aperture 9 through its open end or mouth. If the handle is comparatively large it can enter no 35 further than the adjacent portion 10 of the aperture. The plate and handle are then released and an automatic holding grip on the handle is then instantly had. A medium sized or relatively small handle can pass into 40 the aperture portions 11 or 12 before being released. The entrance of the handle to the aperture and to the different sized portions thereof is facilitated by the outwardly flaring sides 17 provided at the outer end of the aperture or the portion 10, and by the slope or flare on which the shoulders 13 are cut.

The stops 8 maintain the holding plate in a 50 position convenient for initial manipulation. The upward folding of the plate not only moves the same out of the way when not in use but enables the fixture to be packed or sold in very compact and narrow cartons, etc.

From the foregoing description it will be 55 readily seen that I have produced such a device as substantially fulfills the objects of the invention as set forth herein.

While this specification sets forth in detail the present and preferred construction of the device, still in practice such deviations from 60 such detail may be resorted to as do not form a departure from the spirit of the invention, as defined by the appended claims.

Having thus described my invention what I claim as new and useful and desire to secure by Letters Patent is:

1. A handle holding fixture comprising a bracket adapted to be secured against a wall, ears projecting outwardly from the sides of the bracket, a handle-holding plate pivoted on the ears and projecting laterally beyond the ears in front of the same, and stop shoulders formed with said ears to engage the under side of the plate when the latter is disposed at a predetermined angle to a horizontal plane. 70

2. A handle holding fixture comprising a bracket adapted to be secured against a wall, and a plate hinged onto the bracket for vertical swinging movement, said plate having a handle-engaging aperture cut therein and open to one side thereof, said aperture being of greater width than the diameter of a handle to be engaged; the plate being formed so that one edge only of the aperture is on a permanently different level than the other. 75 80 85

3. A handle holding fixture comprising a bracket adapted to be secured against a wall, and a plate hinged onto the bracket for vertical swinging movement, said plate having a handle-engaging aperture cut therein and open to one side of the plate; said plate, when the aperture is engaged with a handle, lying at a slight outward angle below a horizontal plane, and being bent at the side opposite the open end of the aperture so that the front portion of the plate and the corresponding edge of the aperture are always on a lower level than the back portion of the plate and the corresponding edge of the aperture. 90 95

4. A handle holding fixture comprising a bracket adapted to be secured against a wall, and a plate hinged onto the bracket for vertical swinging movement, said plate having a handle-engaging aperture cut therein and open to one side thereof, said aperture being formed as a series of portions of decreasing widths from the outer end of the aperture to the inner end thereof to receive handles of various diameters. 100 105

5. A device as in claim 4, in which the junctions of the different width portions of the aperture with each other, are formed as shoulders having a slope toward the smaller width portions to facilitate the entrance of a handle from one portion to another. 110 115

6. A handle holding fixture comprising a bracket adapted to be secured against a wall, and a plate hinged onto the bracket for vertical swinging movement, said plate having a handle-engaging aperture cut therein and open to one side thereof, said aperture being formed as pairs of straight edged portions of definitely different widths. 120

7. A device as in claim 6, in which each portion of the aperture is narrower at its outer than its inner end. 125

In testimony whereof I affix my signature.
ROY R. HART.
